LIGHTING FIXTURE

Josef Muller, Neheim-Husen, Germany, assignor to
Lenze KG Lichttechnische Spezialfabrik, Neheim-Hus-
ten, Germany

Filed Oct. 24, 1960, Ser. No. 62,582

Claims priority, application Germany Apr. 23, 1960

Term of patent 7 years

(Cl. D48—23)

FIG. 1

FIG. 2

FIG. 3

FIG. 4

FIG. 1 is a perspective view of a lighting fixture embodying my new design;

FIG. 2 is an enlarged end elevational view thereof;

FIG. 3 is a front elevational view thereof; and

FIG. 4 is a bottom plan view thereof.

The side of the lighting fixture not shown is substantially plain and the end not shown is the same in appearance as the end shown.

I claim:

The ornamental design for a lighting fixture, as shown and described.
